PILOT'S SEAT

Kenneth Ahrens, Freeport, N. Y.

Application January 15, 1958, Serial No. 49,262

Term of patent 14 years

(Cl. D15—8)

The single figure in the drawing is a side perspective view of a pilot's seat showing my new design, the dominant features thereof being shown by means of full lines.

The pair of members shown as projecting outwardly from the lower edge of the seat are omitted from the opposite side.

I claim:

The ornamental design for a pilot's seat, as shown and described.
